UNITED STATES PATENT OFFICE.

WELLS M. PROTZMAN, OF OSBORN, AND ALBERT D. RAY, OF CLEVELAND, OHIO.

FLYING-MACHINE.

1,264,331.

Specification of Letters Patent. Patented Apr. 30, 1918.

Application filed October 12, 1917. Serial No. 196,297.

To all whom it may concern:

Be it known that WELLS M. PROTZMAN and ALBERT D. RAY, citizens of the United States, residing at Osborn, in the county of Greene, State of Ohio, and Cleveland, in the county of Cuyahoga and State of Ohio, respectively, have invented certain new and useful Improvements in Flying-Machines, of which the following is a specification.

10 This invention relates to flying machines or air ships of the so-called "heavier than air" type, and it has for its primary object the provision of rotative means for elevating the machine in a vertical direction, 15 maintaining the equilibrium by gyroscopic action, thereby allowing the machine to hover at any desired point in the air.

A further object of the invention is to provide a rotary elevating device having adjustable vanes which, when opened are utilized for raising the craft, and when closed form a rotary aeroplane to maintain equilibrium and act as a parachute for gliding downward.

A still further object of the invention is to provide a machine of this type, with a rotary elevating device having adjustable vanes, the opening and closing of which, and the rotation of the device are readily controlled by the operator.

A still further object of the invention is to provide an adjustable rotary element that can be operated independently of, or in conjunction with the longitudinal propeller.

40 A still further object of the invention is to provide a construction that admits of the oscillation in a longitudinal plane, of the rotary device and its housing, so that it can be adjusted to any desired angle relative to the body of the ship.

With these and other apparent objects in view, the invention consists in certain novel features of construction, combination and arrangement of elements, hereinafter fully described, illustrated in the accompanying drawings, and particularly pointed out in the appended claims, it being understood that various changes of details of the structure may be made without departing from the spirit, or sacrificing any of the advantages of the invention.

In the accompanying drawings which are made a part of the specification, Figure 1 is a top plan view of the improved machine, more or less diagrammatic and with certain portions broken away. Fig. 2 is a side ele-

vation. Fig. 3 is a front end elevation. Fig. 4 is a section on line 4—4 of Fig. 6. Fig. 5 is a detail of the construction which will be identified by the description. Fig. 6 is 60 a fragmentary longitudinal section on an enlarged scale, and Fig. 7 is a top plan view, on the same scale, of the rotary member, showing a small portion of one of the vanes broken away.

65 Similar reference characters are employed to indicate corresponding parts throughout the description and the several figures of the drawings.

In carrying out the invention, the frame 70 is constructed of some light but strong material, such for instance, as bamboo, aluminum, or the like. The shape of the body or frame, and in many respects the details of construction may be similar to well known 75 types of flying machines that have been found practical, modification being made to adapt the structure to the embodiment of the improvements.

Planes 1 of well known practical dimensions and construction are attached to, and supported by the central frame work or body 2. The tail of the machine extends rearwardly as shown and is provided with the ordinary rudders which may be manipulated in the usual or well known manner.

A screw propeller 3 is arranged in front of the structure, and a motor 4 is located in suitable position. In the embodiment as illustrated, the propeller 3 is connected with 90 the motor by the propeller shaft 5 and bevel gears 6 and 7, said gears being driven from the motor by sprockets 8 and 9 and chain 10, a suitable clutch 11 being employed for making and breaking connection of the propeller with the motor when desired.

A transverse shaft 12 is mounted in suitable bearings in side members of the body, and mounted on this shaft, on the exterior of said body, is a frame work which provides a rockable housing for certain mechanism which will presently be described. The frame work just above mentioned, comprises four upright members 13, connecting members 14 and 15 at the top, like members at 100 the bottom, suitable bearing members 16 to accommodate the shaft 12, and members 17 and 18 which provide bearings for a vertical shaft 19.

The shaft 12 is driven by the motor 4, 110 through the medium of the sprocket chain 20, a suitable clutch 22 being employed for

disconnecting the sprocket 21, and thereby throwing the shaft 12 out of operation. The shaft 12 carries a bevel gear 23, which is in mesh with a companion gear 24 on the lower terminal of shaft 19, thereby providing means for driving said shaft. The shaft 19 is provided with a head member 25, in which are hinged a series of radiating plane blades, or vanes 26. The vanes 26 are substantially 10 of the shape shown in Fig. 7, being cut away on one edge for a considerable distance from their periphery, as shown at 26^a, and the edge 26^b of one vane overlaps the hinge portion 26^c of the succeeding vane. This construction provides a radial opening between the vanes from the hinge to the periphery, thereby allowing a free escapement of the spent air, and avoiding a more or less strong, direct downward current. The shaft 20 19 is hollow and a rod 27 is adapted to slide longitudinally in the bore 19^a. A disk 28 is provided on the upper terminal of rod 27, said disk being provided with ears 28^a, equal in number to the number of vanes 26. Connecting rods 29 are hinged to the ears 28^a and have link connections 29^a with the upper surfaces of the vanes 26. The vanes are raised and lowered, or oscillated on their hinges by the sliding operation of the rod 25 27 in the bore 19^a of the shaft 19. When the rod 27 is raised the vanes are opened through the medium of the connecting rods 29, and when the rod 27 is lowered the vanes close, and are held substantially flat by the disk 28 bearing on the central portions of the vanes, as shown in Figs. 6 and 7.

In the present embodiment, the raising and lowering of the rod 27 is brought about by a collar 30 which circumscribes the shaft 40 19. The said collar has an internal annular groove 30^a therein which engages pins 31 attached to the rod 27 and extending through slots 19^a provided in the shaft 19. The collar is operated by a lever 32 and a connecting rod 33 rigidly attached to the collar 30, as shown in Fig. 6.

The rockable frame carrying the rotary mechanism is provided with shoes 34 that bear on segmental rails 35, arranged on both 50 sides of the body. The center from which the segments are described is the center of the shaft 12, on which the frame has its rocking bearing. In the construction as illustrated, the frame is operated, or tilted 55 forward or back, on its bearing, by means of cables 36 and 37, which are attached to the frame, and pass over suitably arranged pulleys 38, to a winch 39 conveniently located on the body of the ship. It will be seen that 60 if the propeller 3 becomes inoperative, from any cause, while the motor and other elements are operative, the rotary mechanism, which is normally operated above the body, may be readily thrown into a position in front of the disabled propeller, and be made

to temporarily perform the function of said propeller until the machine is safely landed.

It will also be understood that the machine may be constructed more compact than shown, and thereby bring the rotor member, 70 or vertical propeller down close to the roof of the lateral planes.

From the foregoing description, it will be seen that this invention provides a lifting propeller which may be controlled to adapt 75 the machine to make ascents and descents, without the necessity of gliding over an inclined plane, that it provides for hovering in the air over any given point, to ascend or descend with greater or less speed, and to 80 make a gliding descent when desired. It will also be seen that the invention provides an air ship which may be readily controlled, and which embodies safety factors of great advantage and importance.

What we claim and desire to secure by Letters Patent is—

1. A flying machine including a frame body having motive means therein, laterally extending planes attached to said body, a 90 propeller driven by said motive means, a rotor mounted above the body, said rotor comprising a series of vanes hinged on radiating bearings attached to a vertical shaft, the free edge of each vane being in a direct radial 95 line and overlapping the hinge portion of the succeeding vane, and the opposite edge of each vane being offset from the radial hinge outward, said vertical shaft being driven by the motive means, and means connected with 100 the upper faces of the vanes for oscillating said vanes on their bearings.

2. A flying machine including a body having motive means therein, a longitudinal propeller driven by said motive means, a 105 vertical propeller driven by said motive means, said vertical propeller comprising a hollow vertical shaft, a series of vanes hinged on radiating bearings attached to said shaft, a slideable rod provided in the 110 bore of the vertical shaft, connecting means from said rod to the upper faces of the vanes for oscillating said vanes on their hinge bearings, and means for sliding the rod in the vertical shaft.

3. A flying machine including a body frame having motive means therein, a longitudinal propeller mounted on the body and driven by the motive means, an auxiliary frame mounted on a transverse shaft journaled on the body, a vertical propeller rotatable in said auxiliary frame, said vertical propeller comprising a tubular axial shaft mounted in bearings on the auxiliary frame, a series of vanes hinged on radiating bearings attached to the head of said vertical shaft, and extending radially beyond the hinged connections, a slideable rod provided in the tubular shaft, connecting means from said rod to the upper faces of the vanes for 120 125 130

oscillating said vanes on their bearings, means for operating said slideable rod, and means for oscillating the auxiliary frame on the transverse shaft.

- 5 4. In a flying machine, a rotor mounted above the body of the machine for propelling said machine vertically, said rotor comprising a hollow vertical shaft, a series of vanes hinged to the head of said vertical shaft, a 10 vertically sliding member operative in the bore of the shaft, a head on said sliding member, connecting rods from said head to the upper faces of the vanes whereby said vanes are oscillated on their bearings by the 15 operation of the sliding member, means for operating said sliding member, and motive means for driving said rotor.

5. In a flying machine a rotor mounted above the body of the machine for propelling said machine vertically, and poising said 20

machine, said rotor comprising a vertical shaft, a series of vanes hinged on radiating bearings attached to the head of the shaft, the free edge of each vane being in a direct radial line and overlapping the hinge portion of the succeeding vane, and the opposite edge of each vane being offset from the radial hinge outward so as to provide a radial opening between the vanes from the hinge portion to the periphery, means for 25 oscillating said vanes on their hinge bearings, and means for driving the rotor.

In testimony whereof we affix our signatures in the presence of two witnesses.
